(57) **CLAIM**

The ornamental design for a bench support, as shown and described.

DESCRIPTION

FIG. 1 is an isometric view of the bench support of the present invention;

FIG. 2 is a front elevation view thereof;

FIG. 3 is a right-side elevation view thereof, the left-side elevation view being a mirror image thereof;

FIG. 4 is a top plan view thereof; and,

FIG. 5 is a rear elevation view thereof.

The broken line depiction is for illustrative purposes only and forms no part of the claimed invention.
